UNITED STATES PATENT OFFICE.

PETER A. SCHWAB, OF NEW YORK, N. Y.

DOOR-LATCH.

1,250,522.

Specification of Letters Patent. Patented Dec. 18, 1917.

Application filed July 31, 1917. Serial No. 183,674.

To all whom it may concern:

Be it known that I, PETER A. SCHWAB, a citizen of the United States, and resident of New York city, in the county of New York and State of New York, have invented certain new and useful Improvements in Door-Latches, of which the following is a specification.

This invention is an improved latch designed to retain a movable member in a closed or other predetermined position and is of that type in which the latch member automatically moves to operative engagement with the retainer upon the closing of the door or other movable member to be retained, but requires to be manually operated to release said door or other member.

Although my invention is adapted to a wide variety of uses where a retainer, latch or catch is desired, I have designed an embodiment of my invention particularly for automobile doors and will refer to my invention in that connection, but of course do not desire to be limited to that use or to the specific form shown except as defined in the claims.

The main objects of my invention are to secure a positive and firm retention of the door, permit the easy closing of the door without manual operation of the latch, facilitate the easy withdrawal of the latch member, prevent the door from being pulled or jarred open without the manual operation of the latch and to reduce the friction incidental to the movements of the latch member both to and from locking position and such slight movements as may be due to warping or twisting of the automobile body or the shaking of the door while traveling over rough roads.

As the most important feature of my invention, I employ as the latch retainer, a roller mounted to freely rotate and I so design the latch member that when in locking position, it overlaps the roller to a distance greater than the radius of the roller and engages with the roller beyond and beneath the center of the latter. Thus there is no rubbing of the parts in closing the door and the roller may freely rotate as the catch slides from it; any tendency of the door to open causes the latch member to tend to move farther into locking position with a consequent slight rotation of the roller; and in fact any

relative movement of the latch member and retainer is accompanied by a corresponding rotation of the roller and a corresponding avoidance of friction between the latch member and retainer. The roller may be easily lubricated so as to turn freely and the lubrication being within the roller is not liable to come in contact with or soil the clothing of persons getting into or out of the car.

In the accompanying drawings, Figure 1 is a transverse section through a portion of the door and door casing in the plane of the latch, said section being taken substantially on the line 1—1 of Fig. 2;

Fig. 2 is a vertical section taken on the line 2—2 of Fig. 1 but on a somewhat smaller scale;

Fig. 3 is a face view of the latch retainer; and

Fig. 4 is a rear view of the latch member and its connections.

In the specific form illustrated, I have shown a portion of a door 10 and a door casing or automobile body 11, both having wooden frames and sheet metal facings or outer walls. Set into the edge of the door casing is a latch retainer illustrated particularly in Fig. 3. This includes a sheet metal plate 12, the center portion of which is preferably countersunk below the side edges or retaining flanges 13, the latter having screw holes or any other suitable means for fastening the plate in position. The frame of the door casing is cut away to a sufficient extent to receive the countersunk body portion 12 of the plate. Secured to this body portion is a second plate or roller carrier 14. The latter preferably has portions thereof struck up to form lugs 15 or journals for a pin. Connecting these lugs is a pin upon which is journaled a roller 16. The roller retainer is so connected to the base plate 12 that the roller extends in a vertical position and may be adjusted horizontally toward or from the surface of the door. As shown, the base plate has slots 17 through which retaining screws 18 on the plate 14 extend. By loosening these screws, the roller may be adjusted toward the left hand from the position shown in Fig. 3.

Rigidly secured to the door is a plate 20 provided with screw holes or other suitable means for facilitating its rigid positioning.

The two vertical edges of the plate are bent back to form lugs 21 and 22 and a portion of the frame of the door in the rear of the plate and between these two lugs is cut away 5 to form the latch recess 23. The latch member is in the form of a metal block 24 riveted or otherwise rigidly secured to a leaf spring 25 disposed in the rear of the plate 20. The latch member projects through an aperture in said plate and one end of the leaf 10 spring is riveted or otherwise rigidly secured to the rearwardly extending flange 21 of the plate. The other flange 22 has a portion 15 bent back to a position substantially parallel to the body of the plate and overlapping the free end of the spring 25 so as to limit the rearward bending movement of the latter and prevent any undue distortion of the spring or the breaking of the latter.

15 For withdrawing the latch member, any suitable operating mechanism may be employed. As shown, the rear surface of the spring member carries an L-shaped lug 26 to which is pivoted a link 27. The latter 20 connects to a handle member 28 intermediate of the ends of the latter. The handle member is shown as being pivotally supported at its lower end to a bracket 29 and with its upper end projecting through a slot 25 in the upper edge of the door.

It will be noted that the spring 25 permits the latch member to swing substantially in the direction of the undercut engaging face of the latch member and that this undercut 30 engaging face, when in operative position, is at an acute angle to the plane of the door and at an acute angle to the two planes 12 and 20. Friction is reduced not only by the use of the roller but by the supporting of the 35 latch member in such a way that it does not rub on the plate 20 in passing through the aperture of the latter.

The only portion of the latch 24 which engages with the roller is that at or closely adjacent to the extreme edge of the undercut face. This edge portion while moving to final position travels along the surface of the roller and when in final position, rests on the latter at a point beyond a diametrical 40 plane through the roller and tangent to the arc through which the door swings upon its hinges. In other words, beyond a diametrical plane substantially parallel to the arrow shown in the upper side of Fig. 1.

45 It will be noted that the latch member has an outer cam surface which may ride over the roller as the door is swung to closed position. The latch member moves back into the recess and the spring is, of course, bent. The instant the latch member 50 passes the highest point of the roller, its pressure against the roller tends to draw the door to final closed position and the latch member when swung in to the final position, as shown in Fig. 1, has its bearing or

retaining face engaging with the roller at a point beyond the center of the latter. In the drawing, the latch member is shown as projecting past the roller to a little greater distance than might be usual in actual practice, this feature being slightly exaggerated in the drawing to make its operation more apparent. A short stop may be provided against which the latch will engage so as to prevent it from swinging all of the way to the final position shown and prevent such a great overlap of the roller. In opening the door, the handle member 28 serves to pull the latch back over the roller and the door is swung in the direction indicated by the arrow at the upper side of Fig. 1.

Having thus described my invention, what I desire to secure by Letters Patent and claim as new is

1. In combination, a door casing, a latch retainer in the form of a rotatable roller, means for securing said retainer to said door casing and permitting the adjustment of the latter toward or from the surface of the casing, a swinging door, and a latch member carried by said door and having a cam surface adapted to ride over said roller during the closing movement of the door and an undercut retaining surface for engaging with said roller at a point beyond and beneath the center of the latter to normally prevent the opening of the door.

2. In combination, a pair of plates, one adapted to be secured to a door and the other adapted to be secured to a door casing, a roller carried by one of said plates and adjustable in a direction at right-angles to its axis toward or from one surface of the door, a spring secured to the other plate and a latch member carried by said spring and having a cam face for riding over said roller during the closing of the door and the bending back of said spring and a retaining face at an acute angle to the plane of said last mentioned plate for engaging with the roller at a point beyond a diametrical plane at right angles to the plane of the door.

3. In combination, a plate adapted to be secured to a hinged door and having a flange at one edge thereof bent back substantially at right angles thereto, and having an opening therethrough adjacent to the opposite edge, a latch supported by said flange and mounted to swing through said opening, said latch having an undercut face, and a rotatable retainer with which the edge of said undercut face may engage during a swinging movement of said latch through a range greater than the radius of said retainer.

4. In combination, a pair of members, one adapted to be secured to a door and the other adapted to be secured to a door casing, a roller carried by one of said members, and a latch member carried by the other member and mounted to swing in respect thereto,

said latch having an undercut face terminating in an edge engaging with said roller during a movement of said latch through a distance greater than the radius of said roller.

5. In combination, a roller adapted to be carried by a door casing, a latch member adapted to be carried by a door and mounted to swing through a distance greater than 10 the radius of said roller, said latch presenting a cam face movable past said roller during the closing of the door and an undercut face terminating in an edge adapted to engage with said roller at a point substantially 15 diametrically opposite to the point at which

the latch first engages the roller during said closing movement.

6. In combination, a roller and a latch member mounted to swing and having a cam face and an undercut face terminating in an 20 edge, the angle of said undercut face being such in respect to the direction of movement of said latch that only the edge portion of said undercut face engages with said roller when in final retaining position. 25

Signed at New York city in the county of New York, and State of New York this 30 day of July, A. D. 1917.

PETER A. SCHWAB.
